SPRAYER

Joseph Walker Patterson, Tulsa, Okla., assignor
to J. A. Vaughan Manufacturing Company,
Tulsa, Okla., a corporation of Delaware

Application January 28, 1933, Serial No. 653,987

11 Claims. (Cl. 299—89)

This invention relates to new and useful improvements in sprayers.

One object of the invention is to provide an improved sprayer for spraying various liquids, 5 such as insecticides, paints and lacquers, as well as oils and other fluids.

A particular object of the invention is to provide a sprayer of the continuous-spray type, which may be made of comparatively few parts 10 and of simple, as well as substantial construction, whereby it will not only be inexpensive to produce and to maintain, but will be easy and simple to operate.

A further object of the invention is to provide 15 a sprayer which, while simple and highly efficient, will operate without leaking and becoming messy; and particularly one in which the nozzle will not drip, and wherein the nozzle will be self-draining, thus not only conducting surplus liquid back into 20 its head, but preventing the ejection of drops of liquids as well as clogging.

Another object of the invention is to provide a unique and substantial connection between the 25 head and receptacle of the sprayer, whereby the head may be firmly seated in the cap of the receptacle and a simple, inexpensive and convenient structure produced.

An important object of the invention is to provide 30 a removable atomizing or eduction tube and a simple and efficient mounting for the tube, whereby the tube is not only effectively held in place in the nozzle, but is readily removable for cleaning and changing.

A further object of the invention is to provide 35 an atomizing or eduction tube co-acting with a nozzle in such a manner as to control the quantity and admission of air under pressure to the tube to promote the spray, and whereby fixed adjustments may be had for fluids of different 40 consistencies, by substituting tubes with corresponding air admitting openings.

Still another object of the invention is to provide 45 a head of such size as to store an adequate supply of air, under pressure, to maintain a continuous spray, as well as a nozzle of simple and non-clogging structure arranged to drain liquids back into the head and made integral with the head, thus making for inexpensive manufacture.

A construction designed to carry out the invention 50 will be hereinafter described, together with other features of the invention.

The invention will be more readily understood 55 from a reading of the following specification and by reference to the accompanying drawings, in

which an example of the invention is shown, and wherein:

Figure 1 is a side elevation of a sprayer constructed in accordance with the invention,

Figure 2 is a longitudinal sectional view of the 60 same,

Figure 3 is an enlarged sectional view of the sprayer head,

Figure 4 is a vertical sectional view taken on the line 4—4 of Figure 3,

Figure 5 is a perspective view of the disk having the spray bracket attached thereto,

Figure 6 is a detail of the check valve,

Figure 7 is an enlarged view of the atomizing tube partly in elevation and partly in section,

Figure 8 is a view of a plurality of atomizing tubes showing each having a different size slot therein, and

Figure 9 is a plan view of the receptacle cap.

In the drawings the numeral 10 designates a 75 sprayer barrel having a plunger 12 slidably therein. A plunger rod 13 has one end secured to the plunger and said rod is supported by and extends through a cap 14 which closes one end of the barrel. A suitable handle 15 is fastened on the outer end of the rod for operating the plunger. Although I have shown a manually operated sprayer, it is to be understood that the invention is not to be limited to this particular type.

A cylindrical head 16, preferably made of brass, 85 or other non-rusting or non-corrosive metal, is provided with an integral collar 17 at its near end. Although it is preferable to make the head of non-rusting or non-corrosive metal, it is to be understood that it can be made of any suitable material. The collar 17 is offset to form an internal shoulder 18. This collar is adapted to fit around the forward end of the barrel 10 (Figures 2 and 3) and may be soldered, or in any other suitable way secured thereto. A disk 19, 95 which separates the interior of the barrel from the head, is confined between the shoulder 18 and the forward end of the barrel.

A tapered or conical nozzle 20 is positioned at the forward end of the head 16 and is preferably 100 made integral therewith. It is noted that the opening in the end of the nozzle is substantially small in proportion to the size of the interior of the head 16. A suitable container, or receptacle, 21 for receiving the liquid to be sprayed is provided with an externally screw-threaded collar or neck 22. A cap 23 is adapted to screw onto the neck of the container to cover the same. A suitable packing gasket 24 is interposed between the upper edge of the neck and the cap.

The cap is provided with a diametrical sump 25 in its top (Figures 4 and 9). The sump conforms to the contour of the cylindrical head 16 and the head is positioned within said sump and 5 is soldered, or in any other way suitably secured thereto, whereby the cap is permanently fastened to the underside of the head. The cap has an opening 26 in its top which registers with an 10 opening 27 in the head when the cap is secured thereto, as is clearly shown in Figure 3. Thus, the openings 26 and 27 provide a communication between the head 16 and the container 21.

An atomizing or eduction tube 28, preferably made of non-rusting or non-corrosive metal, is 15 mounted within the head and has its forward end resting against the inner wall of the nozzle 20. The tube is bent upon itself at substantially a right angle and an offset bend or crook 29 is provided at the intersection of the angular ends. 20 The offset bend 29 engages in a slot 30 of a spring bracket 31 which is secured to the disk 19 and extends forwardly therefrom. It is obvious that the spring bracket will hold the forward end of the tube 28 in position against the inner wall of 25 the nozzle.

The slot 30 is of such length that the top of the tube rests against the upper edge of said slot (Figure 3) and the lower end of the offset bend 29 engages the bottom edge of the slot. With this 30 arrangement the spring bracket not only holds the forward end of the tube firmly against the inner wall of the nozzle, but also prevents any vertical displacement of said tube.

The lower end of the tube 28 depends through 35 the opening 27 in the head and through the opening 26 in the cap into the container 21, which carries the fluid to be sprayed. It is noted that the tube terminates short of the bottom of the container and does not rest on the same, but is supported by the engagement of the offset bend 29 in the slot 30. It is seen that the tube 28 forms a direct communication between the container 21 and the outlet nozzle 20.

A check valve 32 is mounted on the disk 19 40 near the upper end of the same. The check valve is preferably made of non-rusting or non-corrosive metal and may be of any suitable construction, but as a manufacturing expedient, I prefer to utilize the valve as a means of attaching the spring bracket 31 to the disk. The valve 45 includes a head 33 and a tubular shank 34. The shank is inserted through an ear 31' on the upper end of the bracket and then through an aperture in the disk, so that the head holds the bracket 50 in place (Figures 3 and 6). The shank may be soldered, or secured in any suitable way, to the disk. The head is provided with a valve ball 35 which seats against the shank and which is retained within the head by prongs 36, as is clearly 55 shown in Figure 6. It is pointed out that air can pass from the barrel 10 into the head 16, but the check valve will prevent the same from passing from the head into the barrel.

The forward end of the atomizing or eduction 60 tube 28 is provided with slots 28'. With the forward end of the tube in position against the inner wall of the nozzle 20, it is obvious that air escaping from the head must first pass the slots 28' and by varying the size of these slots, the 65 amount of air emitting from the nozzle may be controlled.

In operation the forward stroke of the plunger 12 will force air from the barrel 10 through the check valve 32 and into the head 16. Air in the 70 head will pass downwardly through the openings

26 and 27 into the container 21 above the liquid. Thus, the only escape for the air from the head is through the slots 28' in the forward end of the eduction tube and out through the nozzle 20. The size of the head is such that a large air storage 75 space is provided and since the opening in the nozzle is insufficient to allow all of the air forced into the head by one stroke of the plunger to immediately escape, an air pressure is built up within the head 16 and in the container 21 above the liquid. Continued reciprocation of the plunger 12 will further build up the pressure whereby a continuous stream of air is ejected from the nozzle 80 85 90 95 100 105 110 115 120 125 130 135 140 145 150.

As the air pressure controls the amount of air emitting from the nozzle, it will also control the amount of fluid ejected through the tube, because the air pressure in the head 16 and in the container 21 will equalize itself. As the pressure is built up by continued reciprocation of the plunger 12, the air and liquid streams will be increased proportionately, thereby providing perfect atomization at all times.

By varying the size of the slots 28' in the forward end of the tube 28, it is possible to further control the air emitting from the nozzle. It has been found that in spraying liquids, such as gasoline, naphtha, and the like, which flow freely, a small amount of air will suffice for perfect atomization. However, in spraying liquids, such as paint, it is necessary, because of their heavier consistency, to provide more air to attain perfect atomization. Therefore, it is to be understood that the slots 28' are not to be limited to any particular size or shape, as they may be varied to obtain the best results.

The conical nozzle 20, besides forming a seat to position the forward end of the eduction tube 28, allows any fluid which may collect within the nozzle to drain back into the head, thereby eliminating the ejection of drops of fluid after the sprayer has been operated. Also, the large air space around the end of the eduction tube prevents clogging of the opening of the nozzle. The spring bracket 31 holds the tube 28 firmly in position but yet allows it to be easily removed or replaced.

Manufacturing costs have been reduced to a minimum as no machined parts are necessary. The head and nozzle are made of one piece which 125 is a stamping and can be produced very cheaply. All parts vital to the operation of the device are made of non-rusting or non-corrosive material, thereby making for longer use. The operation is positive, as there are no adjustments to be 130 made.

The description which has been given recited more or less detail of a particular embodiment of the invention, which is set forth as new and useful, however, I desire it understood that the invention is not limited to such exact details of construction, because it is manifest that changes and modifications may be made within the scope of the appended claims without departing from the spirit of the invention.

What I claim and desire to secure by Letters Patent, is:

1. A sprayer comprising a receptacle, a cylindrical air storage head mounted on top of the receptacle, a nozzle extending from one end of the head, a disk closing the opposite end of the head, means for supplying air under pressure to the head, a bent eduction tube open at each end and extending upwardly from the lower portion of the receptacle into the head and forwardly through 145 150

the head to the nozzle, said tube terminating within the nozzle, and spring means mounted on the disk within the head for engaging the tube at the bend between its upwardly and its forwardly extending portions, for pressing its forward end into the nozzle.

2. A sprayer comprising a receptacle, a cylindrical air storage head mounted on top of the receptacle, a nozzle extending from one end of the head, a disk closing the opposite end of the head, means for supplying air under pressure to the head, a bent eduction tube open at each end and extending upwardly from the lower portion of the receptacle into the head and forwardly through the head to the nozzle, said tube terminating within the nozzle, and spring means mounted on the disk within the head for engaging the tube at the bend between its upwardly and its forwardly extending portions, for pressing its forward end into the nozzle, said air supply means including a check valve mounted in the disk and having a portion thereof engaging the spring means for holding it on the disk.

3. A sprayer comprising a receptacle, a cylindrical air storage head mounted on top of the receptacle, a nozzle extending from one end of the head, a disk closing the opposite end of the head, means for supplying air under pressure to the head, a bent eduction tube open at each end and extending upwardly from the lower portion of the receptacle into the head and forwardly through the head to the nozzle, said tube terminating within the nozzle, and spring means mounted on the disk within the head for engaging the tube at the bend between its upwardly and its forwardly extending portions, for pressing its forward end into the nozzle, said spring means having a slot in which the bend is engaged.

4. A sprayer comprising a receptacle, a hollow air storage head mounted on top of said receptacle and having a conical nozzle at its forward end, means for closing the rear end of the head, means for supplying air under pressure to the head, a bent eduction tube open at each end extending from the lower portion of the receptacle through the head to the nozzle, and resilient means in the head for urging the forward end of the tube into engagement with the inner wall of the nozzle, the tube having a side opening within the nozzle for admitting air under pressure from the head.

5. A sprayer comprising a receptacle, a cap removably mounted on the receptacle, a cylindrical hollow head mounted on the cap, the cap and head having connected openings for establishing a passage therebetween, a conical nozzle integral with the front wall of the head, means for supplying air under pressure to the head and receptacle, a bent eduction tube extending through the passage in the head and cap and having one end terminating in the lower portion of the receptacle, and means for urging the forward end of the tube into the nozzle.

6. A sprayer comprising a receptacle, a cap removably mounted on the receptacle, a cylindrical hollow head mounted on the cap, the cap and head having connected openings for establishing a passage therebetween, a conical nozzle integral with the front wall of the head, a barrel attached to the head, a plunger working in the barrel, a disk between the head and the barrel, a check valve mounted in the disk, a bracket mounted in the head, and a bent eduction tube

extending through the passage in the head and cap having one end terminating in the nozzle and the other end terminating in the lower portion of the receptacle, said bracket having means engaging and supporting said tube at the bend thereof.

7. In a sprayer, a receptacle, a cylindrical air storage head mounted on top of the receptacle, a conical nozzle integral with the front wall of the cylinder having an opening in its tip, a disk closing the rear end of the head, a bent eduction tube open at each end and extending upwardly from the lower portion of the receptacle into the head and forwardly through the head to the nozzle, and spring means mounted on the disk within the head engaging the tube at its bend and urging the forward end of the tube into the tip of the nozzle.

8. In a sprayer, a cylindrical air storage head, having a conical nozzle formed integral with the front wall thereof, a liquid storage receptacle suspended from the storage head, a removable bent tube having one leg extending through the air storage head and the other leg dipping into the liquid storage receptacle, and resilient means mounted within the head engaging the tube at its bend and urging the forward end thereof into the tip of said nozzle.

9. In a sprayer, a barrel having a plunger working therein, a cylindrical air storage head fitted to the end of the barrel, said storage head having a conical nozzle formed integral with the forward end thereof, a liquid receptacle suspended from the storage head, a removable bent tube open at each end and having one leg extending into the liquid storage receptacle and the other into the air storage head, a disk separating the air storage head from said barrel, a check valve mounted on said disk, and a spring bracket also mounted on said disk and having a slot therein, the bend of said tube fitting into said slot, said bracket having a portion pressing against the first-mentioned leg, whereby the forward end of the eduction tube is urged into the tip of said nozzle.

10. In a sprayer, an air pressure chamber having a nozzle at the forward end thereof, a liquid receptacle located beneath the air storage chamber, a bent eduction tube open at each end and extending upwardly from the lower portion of the receptacle into the air pressure chamber and forwardly through the chamber to the nozzle, said tube having an upright leg provided with a rearwardly offset portion thereabove, and means bearing against the tube at the base of said rearwardly offset portion for supporting the tube in operative position and holding its forward end firmly in said nozzle.

11. In a sprayer, a receptacle, a cylindrical head mounted on top of the receptacle enclosing an air pressure chamber, a nozzle at the front portion of the cylinder, a bent eduction tube open at each end and extending upwardly from the lower portion of the receptacle into the air pressure chamber in the head and forwardly through the chamber to the nozzle, and guiding and supporting means for said tube within said head, said tube having an upright leg provided with a rearwardly offset portion thereabove, and said guiding and supporting means including a slotted portion coacting with the rearwardly offset portion of the upright leg.

JOSEPH WALKER PATTERSON.
